UNITED STATES PATENT OFFICE

FRED E. SEALEY, OF VERMILION, SOUTH DAKOTA

WHEEL SCRAPER

Application filed November 22, 1930. Serial No. 497,489.

The present invention relates to a wheel scraper designed for use on tractors for use in scraping the front wheels where the same are disposed relatively close together.

An important object of the invention resides in the provision of a scraper of this nature which is exceedingly simple in its construction, thoroughly efficient and reliable in use, adjustable, easy to mount, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of the scraper showing the wheels fragmentarily of the tractor,

Figure 2 is a side elevation of the scraper showing the same applied.

Figure 3 is a sectional view taken substantially on the line 3-3 of Figure 2,

Figure 4 is a top plan view of one end of the scraper,

Figure 5 is a fragmentary section taken substantially on the line 5-5 of Figure 1, and

Figure 6 is a sectional view taken substantially on the line 6-6 of Figure 5.

Referring to the drawings in detail, it will be seen that numerals 5 denote the wheels of the type of tractors wherein the front wheels are disposed closely together being mounted on a dirigible axle 6 in a housing 7.

My improved scraper is formed from a single sheet of resilient metal to form a straight attaching end portion 8 from which extends upwardly and forwardly an arm 9 which merges in to a bight portion 10 curved forwardly and downwardly terminating in downwardly and rearwardly inclined scraper blades which diverge downwardly

from each other and are denoted by numerals 11. The ends of these blades 11 engage with the peripheries of the wheels 5 to the inside of the flanges 5' thereon. In the end 8 there is formed an opening 12 through which extends a screw 14 to engage in the bottom of the housing 7. A block 15 is mounted on the end 8 forwardly of the housing 7 and is adjustably held in place by a bolt and nut 16 passing through the block and through an elongated slot 18 in the end 8. By shoving this block up against the axle housing and tightening the nut on the bolt the scraper is rigidly secured to the axle structure.

It is thought that the construction, utility and advantages of this invention will now be quite apparent to those skilled in this art without a more detailed description thereof.

The present embodiment of the invention has been described in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A scraper of the class described formed from a single sheet of elongated resilient material to provide a relatively straight end portion merging into an upwardly and forwardly inclined arm which in turn merges into a bight curved forwardly and downwardly and terminating in blades which incline rearwardly and diverge downwardly from each other.

2. A scraper of the class described formed from a single sheet of elongated resilient material to provide a relatively straight end

portion merging into an upwardly and forwardly inclined arm which in turn merges into a bight curved forwardly and downwardly and terminating in blades which incline rearwardly and diverge downwardly from each other, said straight end being provided with an opening, a screw for said opening, said straight end being provided with an elongated slot, a block on the straight end, a bolt through the block and through the slot, and a nut and washer on the bolt to tighten the bolt for holding the block in desired adjusted positions on the straight end.

15 In testimony whereof I affix my signature.
FRED E. SEALEY.
